UNITED STATES PATENT OFFICE.

JAMES W. CRONAN, OF TIPTONVILLE, TENNESSEE.

HORSE-DETACHER.

SPECIFICATION forming part of Letters Patent No. 394,157, dated December 11, 1888.

Application filed July 17, 1888. Serial No. 280,182. (No model.)

To all whom it may concern:

Be it known that I, JAMES W. CRONAN, a citizen of the United States of America, residing at Tiptonville, in the county of Lake 5 and State of Tennessee, have invented certain new and useful Improvements in Horse-Detachers, of which the following is a specification, reference being had therein to the accompanying drawings.

10 This invention pertains to certain new and useful improvements in detaching devices for carriages and wagons; and the invention comprises the details of construction, combination, and arrangement of parts, substantially as hereinafter fully set forth, and particularly pointed out in the claims.

In the accompanying drawings, Figure 1 is a front end view of a vehicle, showing my invention as used in practice. Fig. 2 is an enlarged perspective view. Fig. 3 is a vertical sectional view. Fig. 4 is a side view, and Fig. 5 is a detail.

Referring to the drawings, A designates an ordinary singletree of a carriage or wagon, 25 and to the end thereof are secured vertical frames a a , from the lower ends of which project right-angular screws a' a' , designed to be screwed into the ends of said singletree. The upper end of each frame a has a bent 30 arm, a^2 , forming an opening or recess, a^3 , of approximately **U** shape. In the wall of this frame is a vertical slot or opening, b , upon one side of which is formed a shoulder, b' , having an inner beveled surface, b^2 , as shown.

35 B is an approximately **T**-shaped hook pivotally secured at its lower end by a cross-rod, b^3 , in the slot b , and in a groove, b^4 , on the upper rear side of this hook is pivotally mounted a small lever or trigger, C, the upper 40 per shouldered end of which fits over the upper end of hook B. The lower forward end of lever or trigger C is provided with a short lug or projection, d , designed to engage shoulder b' . The lower rear end of said lever or 45 trigger has a short extension, d' , against which bears the upper free end of a spring-plate, d^2 , attached at its lower end to the **T**-shaped hook B.

In practice a cord or strap, D, is connected 50 at its ends to loops or rings e e , attached to the upper end of the levers or triggers C, and to the center of this cord or strap is connected

the lower end of a second cord or strap, e' , which is passed through suitable eyes or guides attached to the dash-board of a vehicle and within convenient reach of the driver. From this it will be seen that by pulling on the cord or strap e' the cord or strap D will affect the pulling on the upper ends of levers or triggers C C, disengaging the lugs thereof 60 from contact with the shoulders b' , and the consequent withdrawal of the projecting ends of hooks B from the apertures in the rear ends of the traces, thus effecting the ready detaching of a horse from a vehicle in case of 65 runaway or accident.

When the hooks B are retaining the traces in place, said hooks are held as against displacement by means of the triggers or levers, the spring-pressure on which holds the lugs 70 thereof firmly against the shoulders of the frames.

I claim as my invention—

1. As an improvement in detaching devices for vehicles, the frames having the approximately **T**-shaped hooks, and the triggers or levers pivoted to said hooks and engaging said frames, and the operating cords or straps, substantially as shown and described. 75

2. As an improvement in detaching devices, the frames having the upper **U**-shaped openings or recesses, the **T**-shaped hooks projecting into said openings or recesses, and the operating cords or straps, substantially as shown and described. 80

3. As an improvement in detaching devices, the frames having the slotted wall and the beveled shoulders, the **T**-shaped hooks, and the spring-held levers or triggers engaging said shoulders, substantially as shown and 90 described.

4. The combination, with the vertical frames having slots and beveled shoulders, the right-angular screws, and the upper bent arms of the **T**-shaped hooks, the levers or triggers 95 having lugs engaging said shoulders, the springs, and the operating cords or straps, substantially as shown and described.

In testimony whereof I affix my signature in presence of two witnesses.

JAMES W. CRONAN.

Witnesses:

W. L. SONNTAG,
R. T. ANDERSON.
